A. I. SANDBO,
GAS ENGINE PRIMER,
APPLICATION FILED FEB. 9, 1917.

1,242,871.

Patented Oct. 9, 1917.

UNITED STATES PATENT OFFICE.

ANTON I. SANDBO, OF ROCK ISLAND, ILLINOIS.

GAS-ENGINE PRIMER.

1,242,871.

Specification of Letters Patent.

Patented Oct. 9, 1917.

Application filed February 9, 1917. Serial No. 147,669.

To all whom it may concern:

Be it known that I, ANTON I. SANDBO, a citizen of the United States, residing at Rock Island, in the county of Rock Island 5 and State of Illinois, have invented certain new and useful Improvements in Gas-Engine Primers; and I do hereby declare the following to be a full, clear, and exact description of the invention, such as will enable others skilled in the art to which it 10 pertains to make and use the same.

This invention relates to a gas engine primer, and has for its principal object to provide a device of this character by which 15 a predetermined amount of fuel can be conveyed from a suitable fuel reservoir to the engine intake manifold, where it is designed to be used for the purpose of facilitating an easy and ready starting of the engine.

20 A further object of the invention is to provide a primer in which another charge of fuel will gravitate into the holding sleeve immediately after the previous fuel charge has been discharged into the conveyer pipe.

25 With these and other objects in view as will appear as the description proceeds, the invention comprises various novel features of construction, combination and arrangement of parts as will be more fully described hereinafter and set forth with particularity in the appended claims.

Referring to the drawings,

Figure 1 is a sectional elevation showing my improved engine primer operatively associated with the intake manifold of the engine.

Fig. 2 is a front elevation of the primer, and

Fig. 3 is a vertical transverse sectional view taken on the line 3-3 of Fig. 2.

Fig. 4 is a vertical sectional view through the holding sleeve and the lower portion of the fuel tank, showing a modified form of the device.

45 Similar characters of reference are used to denote like parts throughout the following description and the accompanying drawings.

Referring more particularly to the drawings, the reference numeral 1 indicates a fuel reservoir, which in this instance is circular in cross section, as clearly shown in Figs. 1 and 2, and is designed to be supported by suitable straps 2, the straps in this instance

being attached to the dash 3 of an automobile. The fuel reservoir is designed to be filled through an opening 4 that is closed by a filler cap 5.

The fuel reservoir has depending from it a holding sleeve 6, the lower end of which is closed by a screw-threaded plug 7 that is provided with a reduced threaded extension or nipple 8, and a conveyer pipe 9 is connected to the nipple through the medium of a union nut 10. This conveyer pipe 9 has its opposite end attached to and intermediate the ends of a horizontally disposed pipe 11, the free ends of which are attached to the opposite ends of the intake manifold 12.

Disposed vertically through the fuel reservoir 1 is a discharge tube 13, the lower end of which extends down into the holding sleeve 6, as indicated by the numeral 14, and the tube is provided with a pair of apertures 15 and 16 adjacent the top and bottom of the reservoir. Disposed through the discharge tube 13 is a needle valve rod 17, the lower end of which is provided with a needle point 18 designed to rest within and normally close the inner end of the discharge opening 19 extending through the plug 7. A collar 20 is carried by the valve rod and supports a flexible or cushioned valve disk 21 that is designed to engage and close the lower end 14 of the discharge tube when the valve rod is lifted to discharge the contents of the holding sleeve. In order that the discharge opening 19 may be immediately closed upon the discharge of the contents of the holding sleeve, an expandable spring 22 is arranged around the depending end 14 of the discharge tube and bears upon the disk 21, the opposite end of the spring bearing against the bottom of the fuel reservoir.

As shown, the holding sleeve 6 is provided at its upper end with a vent pipe 23, which in this instance is arcuately curved around the fuel reservoir and terminates at 100 a point adjacent the top portion thereof.

From the foregoing description, it will be apparent that in the use of the device fuel will gravitate from the reservoir into the holding sleeve through the apertures 16, until the fuel within the holding sleeve has reached the bottom of the discharge tube, the apertures 15 permitting air to enter the

reservoir to displace the fuel discharged to the holding sleeve. When it is desired to allow a charge of fuel to gravitate into the intake manifold, it is simply necessary to 5 lift the needle valve rod 17 which will allow the contents of the holding sleeve to immediately pass into the conveyer pipe, and upon the release of the needle valve rod, the holding sleeve will immediately be filled with 10 another fuel charge.

By the provision of a device of this character, it will be apparent that a predetermined amount of fuel or, in other words, the exact amount necessary to effectively prime 15 the engine can be quickly and readily gravitated into the intake manifold, thus obviating the usual difficulty of either getting too much or too little fuel into the intake manifold.

20 In Fig. 4 of the drawings, it will be seen that the fuel supply tank 1' has depending therefrom a holding sleeve 6', the lower end of which is closed by a screw-plug 7' that is provided centrally with an outlet opening 19'.

Disposed vertically through the fuel tank is a discharge tube 13', the lower end of which extends down into a holding sleeve, as indicated by the numeral 14'. This discharge sleeve, like the sleeve 13, is provided with pairs of apertures 16' which serve the same purpose as the apertures 15 and 16 previously described.

The valve rod 17' in this form of the device is disposed through the discharge sleeve and provided at its lower end with a pair of oppositely disposed conical valves 18' and 20', the former being slightly larger than the latter. These valves will form sort of 35 a weighted end to the valve stem and the valve 18' will be normally seated within the opening 19' by virtue of its own weight. When the valve stem is lifted, the valve 20' will engage within the lower end 14' of the 40 discharge tube and close it to prevent a further discharge of fuel into the holding sleeve.

The vent tube 23' in this instance extends from the holding sleeve directly through the 50 fuel tank adjacent the discharge tube 13'.

From this, it will be seen that the operation of this form of device is substantially the same as the previously described form of device, with the exception that in this 55 modified form, the valve is closed through the medium of gravity, while in the former device a coil spring is used to close the valve.

in addition to the gravity closing of the valve.

What I claim to be new is:—

60 1. A gas engine primer comprising a fuel reservoir, a holding sleeve depending from the reservoir and provided with a vent opening, a conveyer pipe attached to the lower end of said sleeve, a discharge tube disposed through the fuel reservoir and projecting into said holding sleeve, said discharge tube being provided adjacent the top and bottom inner surfaces of the reservoir with a pair of apertures, and a valve rod disposed through 65 the holding sleeve and the discharge tube and adapted to alternately close and open the bottom of the discharge tube and the holding sleeve.

70 2. A gas engine primer comprising a fuel reservoir, a holding sleeve depending from the reservoir and provided with a vent opening, a conveyer pipe attached to the lower end of the holding sleeve, a discharge tube disposed through the reservoir and projecting into the holding sleeve, said discharge tube being provided adjacent the top and bottom inner surfaces of the reservoir with pairs of apertures, a needle valve rod disposed through 75 said discharge tube and adapted to normally close the conveyer pipe, a disk valve arranged on the valve rod and adapted to close the lower end of the discharge tube when the valve rod is lifted to open the conveyer pipe, and an expansible 80 spring arranged between the valve disk and the bottom of the reservoir.

75 3. A gas engine primer comprising a fuel reservoir, a holding sleeve depending from the reservoir and provided with a vent opening, a plug valve seat connected to and closing the lower end of said holding sleeve, a conveyer pipe attached to the lower end of 90 said plug valve seat, a discharge tube disposed through the fuel reservoir and projecting into said holding sleeve, said discharge tube being provided at points within the fuel reservoir with apertures, and a valve rod disposed through 95 said holding sleeve and the discharge tube and adapted to alternately open and close the bottom of the holding sleeve and the discharge tube.

100 In testimony whereof I have signed my name to this specification in the presence of two subscribing witnesses.

ANTON I. SANDBO.

Witnesses:

FRED GRUBY,
CHAS. GINNANE.
